UNITED STATES PATENT OFFICE.

ALBERT SANFORD, OF OSHKOSH, WISCONSIN.

COLD SHUT OR OPEN LINK.

SPECIFICATION forming part of Letters Patent No. 387,110, dated July 31, 1888.

Application filed January 14, 1888. Serial No. 260,758. (No model.)

To all whom it may concern:

Be it known that I, ALBERT SANFORD, of Oshkosh, in the county of Winnebago and State of Wisconsin, have invented certain new and useful Improvements in Cold Shut or Open Links; and I do hereby declare the following to be a full, clear, and exact description of the same, reference being had to the accompanying drawings, forming a part of this specification, and to the figures and letters of reference marked thereon.

This invention has reference to that class of separable links such as are employed for uniting links or sections of chain, forming swivels, eyes, &c.; and it consists in the novel and improved construction and formation of such link, whereby a strong but relatively light link is produced, which can readily be inserted and securely fastened in place, all as hereinafter more fully described, and pointed out in the claims.

In the accompanying drawings, Figure 1 is a view in perspective of my improved link or blank previous to closing. Fig. 2 is a side view showing the link closed. Fig. 3 represents the cross-bar or pin in longitudinal and transverse sections. Fig. 4 represents the bow of the link. Fig. 5 is a transverse section through the bow.

Similar letters of reference in the several figures indicate the same parts.

My improved link, constructed of malleable metal, preferably iron or steel, is forged, cast, or otherwise formed in substantially the shape shown—that is to say, with a bow, A, of U or other desired form, one end or leg provided with an eye, B, while the other carries a transverse cross bar or pin, C, rigidly attached at one end to one leg of the bow A, the opposite end, c, standing in line with the opening in eye B, but separated therefrom a sufficient distance to permit the passage of a link, ring, or other device to which the link is to be attached. The link is of the kind known as "cold shut"—that is to say, one which is bent or forced together or into final form and secured while cold. To effect this operation, the arms of the bow A are forced together until the end c of the pin C is passed into and through the eye B, when the end is spread or riveted outside the contracted orifice in eye B. This orifice

may be of any desired form, the end of the pintle being properly fitted thereto.

The bow or pin, or both, are made hollow to render the link lighter, and in order to preserve the strength of the parts and the integrity of the wearing faces, as well as to facilitate their manufacture, the blanks for the links are formed with the bow and pin open on the back or outer faces, as illustrated in Figs. 3 and 5. The opening or recess in the back of the bow terminates at or below the eye B on one side and the junction of the pintle and bow on the other, while the groove or recess in the back of the pin extends from one leg to a point at or near the inner face of the eye B when the link is closed, leaving the end c of the pintle, as well as the angle or junction of pin and bow, solid. The recess in the pin is preferably formed with inclined or beveled ends c', as shown in Fig. 3, to strengthen and stiffen the pin at the points of connection with the bow. These inclines c' also assist in sustaining the pin during the riveting operation, the link being then held with the base of the pin resting upon an anvil, while the end c of the pin is spread or riveted down by blows of a hammer. To facilitate the riveting operation, the face of the end c of the pin is countersunk, so that it can be more readily spread while cold.

The blank with the grooved bow and pin is finished by forcing the two walls or sides of the recess together until their edges meet, thereby forming a completed link with tubular or hollow pin and bow, the central portions of those parts designed to receive the greatest amount of pressure or strain being re-enforced, and thereby prevented from collapsing or yielding by the two meeting edges of the side walls, which latter form a fin or ridge projecting from the outer face and in the plane of the link.

Having thus described my invention, what I claim as new is—

1. In a link such as described, the combination of a hollow bow, a pin or cross-bar secured to one leg, and an eye formed on the other leg and adapted to receive the end of said pin, substantially as described.

2. In a link such as described, the combination, with the bow provided with an eye on one leg, of a cross-bar or hollow pin rigidly attached to the opposite leg and adapted to enter the

eye and be secured therein, substantially as described.

3. The improved link herein described, consisting, essentially, of the bow recessed in the back or outer face with the sides of the recess brought together, one leg of said loop provided with an eye and the other with a pin or cross-bar adapted to enter said eye, substantially as described.

10 4. The improved link herein described, provided with a hollow bow and strengthening-rib formed by the meeting edges of its recessed back or outer face, and carrying on one leg an eye and on the other leg a hollow cross-bar or pin adapted to enter said eye, substantially as described.

15 5. In a link such as described, the combination of the hollow bow and its strengthening-rib, the hollow cross-bar or pin united to the solid end of one leg, and the solid eye formed on the opposite leg and in line with the end of said cross-bar or pin, substantially as described.

20 6. In a link such as described, the combination, with the bow provided with an eye on one

leg, of the cross-bar or pin formed integral 25 with the opposite leg and provided with a recess in its back or outer face, terminating at each end in inclined walls or shoulders, the edges of the sides of said recess abutting together to form a strengthening-rib, substantially 30 as described.

7. The improved cold-shut link herein described, consisting, essentially, of a bow recessed on its outer face, the edges of the walls of the said recess abutting together to form a 35 strengthening-rib, an eye formed on one leg of said bow, a cross-bar or pin united to the solid end of the opposite leg, said cross-piece being recessed on its outer face and provided with a strengthening-rib formed by the abutting edges 40 of the recess, while the end of the cross-bar which is adapted to enter the eye is countersunk, as and for the purpose set forth.

ALBERT SANFORD.
